CLAIM

The ornamental design for a cabinet handle, as shown and described.

DESCRIPTION

FIG. 1 is a perspective view of a cabinet handle showing our new design;

FIG. 2 is a top view of the handle shown in FIG. 1;

FIG. 3 is a front view of the handle shown in FIG. 1; and,

FIG. 4 is a side view of the handle shown in FIG. 1.

Portions of the cabinet handle of FIGS. 1-4 that are shown as broken lines are for illustrative purposes only and form no part of the claimed design.
